CLAIM

I claim the ornamental design for a digital audio memory recorder, as shown and described.

DESCRIPTION

FIG. 1 is a top perspective view of a digital audio memory recorder of the present invention;

FIG. 2 is a top view thereof;

FIG. 3 is a bottom view thereof;

FIG. 4 is a first side view thereof;

FIG. 5 is a second side view thereof;

FIG. 6 is a third side view thereof; and,

FIG. 7 is a fourth side view thereof.
